F i g. 2

Fig. 3Fig. 4Fig. 5

FIG. 1 is a top perspective view taken from the top and one side of a coffee urn showing our new design; FIG. 2 is a front elevational view thereof;

FIG. 3 is a rear elevational view thereof;

FIG. 4 is a side elevational view of the side opposite to that side shown in FIG. 1; and

FIG. 5 is a fragmentary cross sectional view taken along line 5-5 of FIG. 2.

The dominant features of our design reside in the portions shown in full lines.

We claim:

The ornamental design for coffee urn, substantially as shown and described.
